UNITED STATES PATENT OFFICE.

EDWARD ERICKSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

1,425,516.

Specification of Letters Patent. Patented Aug. 15, 1922.

Application filed March 23, 1918. Serial No. 224,186.

To all whom it may concern:

Be it known that I, EDWARD ERICKSON, a citizen of the United States, residing at Beverly, in the county of Essex and State of Massachusetts, have invented certain Improvements in Fastening-Inserting Machines, of which the following description, in connection with the accompanying drawings, is a specification, like reference characters on the drawings indicating like parts in the several figures.

This invention relates to machines for inserting fastenings in shoes, and more particularly to machines constructed and arranged to insert a plurality of fastenings at one operation into shoe parts to secure the same in place.

An object of the invention is to provide a satisfactory duplex or plural fastening inserting mechanism which will be adapted to drive the fastenings in very close juxtaposition, while at the same time being capable of a substantial range of variation in fastening positions, and which will be simple and economical as well as convenient and rapid in operation. The invention is herein shown for the purpose of illustration, but not by way of limitation, as embodied in a machine designed with especial reference to use for inserting fastenings to secure shank stiffeners to the soles of shoes.

Important features of the invention consist in a novel and improved organization whereby provision is made for the desired adjustments of the fastening inserting mechanisms. In the illustrated embodiment of the invention these mechanisms are constructed and arranged for simultaneous and uniform adjustment toward or from each other, means being provided to secure them in any adjusted position. As shown, the fastening inserting mechanisms are pivotally mounted to move inwardly over the soles of shoes and have associated with them controlling means arranged to swing the fastening inserting mechanisms about their axes for effecting uniformly equal and opposite adjustments of said mechanisms about their axes of pivotal mounting.

These and other features of the invention, including numerous details of construction and combinations of parts, will be more fully explained in the following description and then pointed out in the claims.

In the drawings, which represent one embodiment of the invention,—

Figure 1 is a front view of the fastening inserting machine;

Fig. 2 is a view in side elevation of the same machine; and

Fig. 3 is a detail showing the presentation of the work to the fastening inserting devices.

The illustrated embodiment of the invention comprises a fastening supplying mechanism 4 of any well-known type, which separates two fastenings at a time and delivers them simultaneously to delivering tubes 6 which deposit the fastenings in the desired location in the fastening inserting mechanisms.

In performing the special work for which this machine is designed two only of the fastening inserting mechanisms 8 are provided, though it will be understood that a larger number could well be arranged in pairs in the manner shown should it be found desirable to insert a larger number of fastenings than is here considered necessary. Inasmuch as the fastening mechanisms are identical in construction and operation, a description of one will apply equally well to the other. For the purposes of illustration, each inserting mechanism is shown as comprising a substantially tubular driver guide 85

10 pivoted at 12 to the frame 14 of the machine. The guide members 10 are pivoted at their upper ends so that the lower ends may be adjusted toward and from each other by any suitable means, a preferred form of which will now be described. Each guide member 10 is preferably provided with a projecting stud 16 which extends into a cam slot 18 in a member 20 rotatably mounted at 22 on the frame of the machine. It is obvious that upon depressing the handle 24 (in Fig. 1) on member 20, the fastening inserting devices will be caused to separate or recede from one another. Upon turning the handle in the opposite direction, the said mechanisms will be adjusted toward each other to drive the fastenings in close juxtaposition. Mounted in each driver guide 10 is a driver bar 26 having at its lower end a driver 28. Each driver bar is connected to the crosshead 30 preferably by means of a block 32 slidable in a T-shaped slot in the crosshead, there being a ball and socket con-

nection 34 between the driver bar and the slideable block 32. The crosshead 30 is guided in its vertical reciprocations in a practical form of the invention, by means of a guiding bar 36, the lower end of said bar being threaded into a forwardly projecting portion 38 of the machine frame and having its upper end projecting into a socket 40 in the said crosshead. Preferably the means 5 for reciprocating the crosshead consists of a cam 42 at the front end of the shaft 44, said crosshead being urged downwardly on its operative stroke by means of the spring-operated lever 46, there being interposed between said lever and the upper end of the crosshead the usual link connection 48. In order to lessen the jar of the machine and to limit the downward movement of the crosshead, a buffer 50 is provided consisting preferably of leather disks surrounding the guiding bar 36.

It will be observed that the fastening inserting mechanisms are so arranged that each is inclined downwardly and inwardly 25 so that a fastening driven thereby has its point directly toward the median line of the shoe as it is driven through the shank stiffener member in securing the same to the sole of the shoe. As the shoe bottom 30 is slightly convex at the part where fastenings are to be inserted, the inclined inserting mechanisms drive the fastenings in a direction substantially normal to the shoe bottom. In adjusting the fastening inserting 35 devices with respect to each other, the securing member 52 is manipulated to release the cam member 20 which may then be turned to effect the adjustment of the fastening inserting mechanisms with respect 40 to each other, after which the securing member 52 is again adjusted to hold the cam member fixedly in position. In the operation of the machine two fastenings are separated from the fastenings in the race- 45 ways and delivered simultaneously to the tubes 6 while the drivers are in raised position. Each fastening inserting device is provided at its lower end with a nozzle 54 to hold and properly guide the fastening 50 while it is being driven. This nozzle may be of any of the well-known types but is preferably like that disclosed in the patent granted to Nye and Copeland, No. 464,200, December 1, 1891. When the drivers descend they drive the fastenings from the nozzles into each side of the shank stiffener 55 which has been properly positioned upon the shoe bottom as indicated in Fig. 3. The machine has been provided with a one-revolution clutch so that the workman must depress the treadle each time a shoe is presented to the fastening inserting mechanisms for the insertion of fasteners. Preferably the shaft and the brake member and clutch 60 are so arranged that the shaft comes to rest 65

with the drivers in raised position and with fastenings delivered to each fastening inserting mechanism in order that fastenings may be instantly driven in the succeeding cycle of operations upon depressing the treadle. Obviously, it is a distinct advantage to be able to secure the shank stiffener in place at one operation of the machine, it having been necessary heretofore to present the shoe twice in succession to a tacker of the old type to accomplish the same desired result.

Having described my invention, what I claim as new and desire to secure by Letters Patent of the United States is:—

1. In a fastening inserting machine, a supporting frame, a plurality of fastening inserting mechanisms pivotally mounted on said frame for movement about substantially horizontal axis and means for adjusting said mechanisms simultaneously toward and from each other about their axes, said means being constructed and arranged to operate positively so that the extent of adjustment of both mechanisms is invariably the same. 90

2. In a fastening inserting machine, a supporting frame, a plurality of fastening inserting mechanisms pivotally mounted on individual axes in said frame, and manually operated means for adjusting said mechanisms simultaneously toward or from each other about their axes while the machine remains at rest. 95

3. In a fastening inserting machine, a supporting frame, a plurality of fastening inserting mechanisms pivotally mounted in said frame on individual axes, and a manually operated cam member for simultaneously adjusting said mechanisms toward or from each other. 100

4. In a fastening inserting machine, a supporting frame, a fastening inserting mechanism comprising a combined fastening and driver guide pivoted on the frame, a pivotally mounted driver co-operating with the guide to drive fastenings, and a cam member movable for adjusting said guide and driver about their pivot point while the machine remains at rest. 110

5. In a fastening inserting machine, a supporting frame, a plurality of fastening inserting mechanisms mounted in said frame, a cam for simultaneously adjusting said mechanisms toward or from each other, and means for fixedly securing the mechanisms in adjusted position. 115

6. In a machine for tacking shank stiffeners in place in a shoe, a plurality of tacking mechanisms arranged to drive tacks on each side of the median line of a shoe, a tacking mechanism on one side being inclined with respect to the corresponding tacking mechanism on the other side, and means under the control of the operative for simultaneously adjusting the mecha- 120 125 130

- nisms toward or from each other, and varying the angle at which the mechanisms are inclined.
7. In a machine for tacking shank stiffeners in place in a shoe, a plurality of tacking mechanisms arranged to drive tacks on each side of the median line of a shoe, the tacking mechanisms being inclined downwardly toward the vertical plane passing through said median line, means for adjusting the mechanisms toward or away from said plane, and means for securing the mechanisms fixedly in adjusted position.
8. In a fastening inserting machine, a plurality of fastening inserting mechanisms comprising drivers, a cross-head for operating said drivers to drive the fastenings, the cross-head and drivers being slidably and pivotally connected to permit adjustment of the drivers toward and from each other, a single guide for said cross-head located in a plane between the mechanisms, and means located above the cross-head for reciprocating the crosshead.
9. In a fastening inserting machine, a plurality of fastening inserting mechanisms, a cross-head for operating said mechanisms to drive fastenings, a single guide for the cross-head comprising a rod passing through the cross-head, a buffer for the cross-head arranged between the cross-head and said guide and positioned by said rod, and spring means for causing the operative stroke of the cross-head.
10. In a fastening inserting machine, fastening inserting mechanisms arranged in close juxtaposition to each other to drive fastenings through a shank stiffener member and into a shoe sole to secure a shank stiffener in place, means for operating the inserting mechanisms to drive said fastenings substantially simultaneously in order to secure the stiffener in place at one operation of the machine, and a single means for adjusting the mechanisms to vary the spacing between driven fastenings in accordance with variations in the width of shank stiffeners.
11. In a fastening inserting machine, fastening inserting mechanisms arranged in close juxtaposition to each other to drive fastenings through a shank stiffener member and into a shoe sole to secure a shank stiffener in place, means for operating the inserting mechanisms to drive said fastenings substantially simultaneously in order to secure the stiffener in place at one operation of the machine, a single means for adjusting the mechanisms toward or from each other, and a single means for securing said mechanisms fixedly in adjusted position.
12. In a fastening inserting machine, fastening inserting mechanisms arranged in close juxtaposition to each other to drive fastenings through a shank stiffener member and into a shoe sole to secure a shank stiffener in place, means for operating the inserting mechanisms to drive said fastenings substantially simultaneously in order to secure the stiffener in place at one operation of the machine, and means for adjusting the mechanisms simultaneously toward or from each other and for simultaneously fixing them in adjusted position.
13. In a fastening inserting machine, a supporting frame, a plurality of fastening inserting mechanisms pivotally mounted on said frame for movement about substantially horizontal axes, and means for effecting uniformly equal and opposite adjustments of said mechanisms about their axes of pivotal mounting.
14. In a fastening inserting machine, a supporting frame, a plurality of fastening inserting mechanisms pivotally mounted on individual axes in said frame, and manually operated means for effecting simultaneously equal and opposite adjustments of said mechanisms about their axes of pivotal mounting while the machine remains at rest.
15. In a fastening inserting machine, mechanism for inserting fastenings comprising a fastening driver, mechanism for supplying fastenings to the inserting mechanism, power means for operating said mechanisms comprising a shaft having a cam for lifting said driver, said supplying mechanism operating normally to supply fastenings to the inserting mechanisms at the end of each cycle of operations of the machine and at a time when said cam has lifted the driver to approximately its highest point, and a spring mechanism arranged to cause the driving stroke of the driver at the beginning of the next cycle of operations of the machine.
16. In a fastening inserting machine, a supporting frame, a plurality of fastening inserting mechanisms mounted in said frame, a rotatable cam for simultaneously adjusting said mechanisms toward or from each other, and means for securing the cam in adjusted position.
- In testimony whereof I have signed my name to this specification.

EDWARD ERICKSON.
